FLASHLIGHT

Frank G. Stimson, Belleville, N. J., assignor to
 Bond Electric Corporation, Jersey City, N. J.,
 a corporation of Delaware

Application October 5, 1933, Serial No. 692,233

4 Claims. (Cl. 240—10.63)

This invention relates to electric hand lanterns or flashlights of the kind in which a removable battery of dry cells is connected and disconnected at will to an incandescent lamp from which the light is reflected in a given direction.

One object of the present invention is an electric hand lantern in which the light from the lamp may be selectively thrown as a beam or spotlight, that is, concentrated on one spot or diffused over a wider area. Accordingly, a reflector is provided normally directing the light from the lamp in parallel rays and a light diffusing screen is movable between the lamp and the reflector to diffuse the light rays.

The invention also has to do with instrumentalities whereby the light from the light source may be concentrated or diffused. To this end, a sleeve, preferably of frosted glass, is disposed axially of the lamp and is movable, say, by means of a lever between a position between or surrounding, as the case may be, the lamp with respect to the reflector, and a position in which the light rays are not intercepted by the screen.

The invention further seeks a circuit closer for a hand lantern which is incorporated in the handle.

Another object of the invention is a hand lantern which is practical from the standpoint of ease and cheapness of manufacture and durability and effectiveness in use.

These and other objects of the invention and the means for their attainment will be more apparent from the following detailed description, taken in connection with the accompanying drawing illustrating one embodiment by which the invention may be realized, and in which:

Figure 1 is a longitudinal, vertical sectional view of the hand lantern of this invention, showing the diffusing screen in light diffusing position;

Figure 2 is a view showing the hand lantern of this invention in front elevation, parts being broken away to show details of the interior construction;

Figure 3 is a fragmentary view showing the diffusing screen in retracted position whereby the light is concentrated; and

Figure 4 is a fragmentary detail view taken in a transverse plane indicated by the line 4—4 of Figure 1.

Referring now to the drawing, the lantern of this invention generally comprises a cylindrical casing 1 adjustably mounted, as at 2, upon the upstanding brackets or arms 3 of a base 4, the casing being provided with a removable cover 5 through which access may be had to the interior

for replacement of batteries and other parts. At the front end of the casing, that is, the end opposite to the removable cover 5, a cylindrical portion 6 of reduced diameter is provided defining an annular shoulder 7 and the cylindrical portion 6 is formed with threads to receive a threaded cylindrical reflector support 8, which is formed at its outer end with an inwardly directed flange 9 on which the edge of the reflector 10 rests. Outwardly of the reflector 10 is disposed the lens 11, which is secured as by a lens ring 12 threaded on to the tubular member 8. The reflector 10 is formed with a circular aperture 13 for the reception of a lamp 14. By screwing the tubular member 8 on and off the threaded cylindrical end 6, the reflector may be adjusted with respect to the lamp so that the desired focus may be attained.

Within the casing 1 and against the shoulder 7 is disposed a disc 15 preferably of non-metallic or non-conductive material formed with a central aperture 16 of a diameter substantially equal to that of the aperture 13 in the reflector. This disc 15 carries conducting members 17 by which appropriate terminals of the dry cells 18 are connected in series.

Centrally of the casing 1, or co-axially thereof, is disposed a tubular bearing member 20 which is conveniently supported and positioned therein by forming a portion thereof with a bulbous or substantially spherical surface 21 which is engaged by the correspondingly formed ends 22, Figure 4, of a pair of downwardly depending bracket members 23, the upper ends 24 of which are outwardly curved and are conveniently secured, as by welding, to the upper portion of the casing. The bearing member 20 is supported in place by drawing the ends 22 into clamping engagement with the surface 21 by means of the screw and wing nut 25. The bulbous surface 21 provides a ball and socket joint with the surface of members 22 to permit adjustment of the tubular bearing member 20 (which also carries the lamp 14), so that the filament of the lamp can be made to coincide axially with the focal point of the reflector 10. This enables the user to compensate for errors in manufacture of lamps wherein the filament is not on the center line of the lamp.

Surrounding the tubular member 20 is an arcuate positioning member 26 by which a plurality of the dry cells 18 are positioned. Appropriate terminals of the cells 18 are connected in the series at the rear end, as by conducting members identical with the conducting members 17 at the front end and indicated by the reference character 17B.

55

At its forward end, the tubular member 20 is disposed within the aperture 16 and is formed with a lamp socket 30 terminating in a rod-like contact member 31 suitably insulated therefrom as by a tubular bushing 32, said contact member 31 being suitably connected, as by a conductor 33, with that terminal of the battery at the rear of the lantern. A conductor 35 connects the battery terminal at the front end of the lantern with one contact 36 of a circuit closer disposed within the handle 37 of the lantern. The other contact of the lamp is grounded as is also the other terminal of the lamp in that the other terminal of the lamp is in electrical communication through the socket 15 30, tubular member 20 and bracket 23 with the casing 1, which is in turn in electrical connection through the metallic handle member 40 with a movable metallic thumb piece 54, 55 carrying the switch contact 41, as will be apparent.

20 The forward end of the tubular axial member 20 serves as a bearing or support for a reciprocable translucent screen 45 concentric with the tubular member 20 and movable through the apertures 16 and 13 from a position within the reflector surrounding the lamp 14 to a position, as shown in Figure 3, without the reflector exposing the lamp. The inner end of the translucent screen is provided with an annular frame 46 conveniently clamped thereto to which is pivotally mounted, as at 47, a bifurcated operating lever 48 fulcrumed, as at 49, on a portion of the bracket 23 and extending through a slot 50 in the casing whereby the end is exposed for manual actuation.

25 The handle is tubular, as at 53, and is preferably of conductive or metallic material to form part of the electrical circuit. The contact member 41 is axially disposed within the tubular handle 37 and is threaded, at its forward end, in a metallic plug 54 slidable in handle 37 and having a cylindrical thumb piece 55 protruding through an aperture in the front end of a handle. The plug 54 is normally urged to the forward end of the handle by the spring 56, thereby carrying the contact member 41 out of contact with the 30 contact member 36.

The contact 36 is illustrated as a cylindrical plunger movable in a guideway 57 in an insulatory plug 58 in the rear end of the handle 53. It is formed rearwardly with a flange adapted to abut 35 against a shoulder formed by a passage of larger diameter in the plug 58 and is urged forwardly by a spring 59 bearing against a terminal member 60 to which the lead 35 is secured, as by a set screw 61 threaded into the plug 58 and accessible 40 by means of the removable cover 62.

To close the circuit, the thumb piece 55 is pressed inwardly, thereby carrying the contact 41 into electrical connection with the yielding contact 36 and closing the circuit through the batteries and lamp. To hold the circuit closed, the thumb piece 55 may carry an actuating locking pin 65 passing through a cam slot 66 in the sleeve 53, say, which when pressed will follow the slot to turn the plug 55 about its axis and move it 45 rearwardly and retain it in circuit making position. The circuit is opened by moving the pin in the other direction.

The translucent screen 45 may conveniently be made of frosted glass or the equivalent and when 50 the screen 45 surrounds the incandescent lamp, as shown in Figure 1, light rays from the lamp fila-

ment passing through the screen, are diffused and broken up and reflected in various directions from the reflector to spread the light over a relatively wide area. On the other hand, when the frosted tube 45 is retracted, as shown in Figure 3, so as to uncover the lamp, the light rays therefrom will be parallel and, falling on the reflector, will be reflected in a parallel beam and concentrate the light on a spot of relatively small area.

It will thus be seen that a hand lantern has been provided which may be carried about in the hand by means of a handle 37 or stood upon the base 4. The circuit is easily closed to illuminate the lamp by depressing the push button 55 in the handle, which is disposed convenient to, say, the thumb. Similarly, the light may be changed from a flood light to a spot light by simple actuation of the handle 48.

Various modifications will occur to those skilled in the art in the configuration, disposition and composition of the component elements going to make up the invention as a whole and no limitation is intended by the phraseology of the foregoing description or illustrations in the accompanying drawing.

What is claimed is:—

1. In an electric hand lamp, in combination, a casing, a member whereof the axis is substantially coaxial with the casing axis and which is formed with depressed cell positioning portions and conductive means at either end of said member alternately connecting unlike terminals of adjacent cells.

2. In an electric hand lamp, in combination, a casing, a member whereof the axis is substantially coaxial with the casing axis and which is formed with depressed cell positioning portions, non-conductive walls at the ends, respectively, of said cell positioning member and conductive means carried with said walls alternately connecting unlike terminals of adjacent cells.

3. In an electric hand lamp, in combination, a casing, a lamp socket support axially of the casing, an elongated cell positioning member substantially U-shaped in cross-section within which said lamp socket support is disposed, said cell positioning member being formed with depressed cell positioning portions, non-conductive walls at the ends, respectively, of said tubular cell positioning member and conductive means carried with said walls alternately connecting unlike terminals of adjacent cells.

4. In an electric hand lamp, a cylindrical casing formed with a restricted threaded end defining an inward shoulder, a lens ring threaded on said end, a removable closure for the other end of the casing, spaced non-conductive walls within the casing formed axially with apertures, respectively, a cylindrical lamp socket support disposed axially of the casing and extending within the apertures in the non-conductive walls, a centrally disposed generally tubular member formed with depressed cell positioning portions within which said lamp socket support is disposed, said cell positioning member being formed with depressed cell positioning portions and conductive means carried with said walls alternately connecting unlike terminals of adjacent cells.
